P. DE CLAMECY,
TYPE WRITING MACHINE,
APPLICATION FILED MAR. 4, 1916.

1,280,678.

Patented Oct. 8, 1918.

UNITED STATES PATENT OFFICE.

PHILIPPE DE CLAMECY, OF BOSTON, MASSACHUSETTS, ASSIGNOR TO CORONA TYPE-WRITER COMPANY, INC., A CORPORATION OF NEW YORK.

TYPE-WRITING MACHINE.

1,280,678.

Specification of Letters Patent. Patented Oct. 8, 1918.

Application filed March 4, 1916. Serial No. 82,137.

To all whom it may concern:

Be it known that I, PHILIPPE DE CLAMECY, a citizen of the United States, and a resident of Boston, county of Suffolk, and State of Massachusetts, have invented certain new and useful Improvements in Type-Writing Machines, of which the following is a full, clear, and exact description.

This invention relates more particularly to the platen carriages of front strike or other visible typewriting machines.

So far as I am aware, the carriages of typewriting machines are adapted to support paper or other work sheets of a length approximately the length of the platen but not sheets of paper, envelopes and the like which are much wider than the length of the platen carriage. To accomplish this result, it is the usual practice to provide carriages of different lengths which are for the most part interchangeable. In such cases and particularly for machines which are of a portable character, as the Corona typewriter for example, the additional length of the carriage would be objectionable whether as a separate attachment or as a part of the machine because the machine would thereby lose much if not all of its compact portable character.

The primary object of the present invention is to provide a platen carriage which is particularly adapted for small portable typewriters of a folding character, though also adapted for other makes of typewriters, and which carriage and platen are of such a construction that wide sheets of paper, long envelopes, or other sheets may be placed about the platen so as to extend beyond the ends thereof and the carriage operated in a manner similar to the ordinary carriage.

Another object of the invention is to provide a carriage in which the platen is substantially floating and entirely free of end supports so that the work sheet may extend a considerable distance beyond the ends of the platen and carriage without interfering with the travel of the carriage or the manipulation of the work sheet.

Other objects of the invention are to provide simple and efficient means whereby the platen may be kept in proper alinement while in use; to provide simple means whereby the work sheet may be properly guided about the platen; and to provide means whereby the work sheet may be released to

adapt the same to be adjusted about or lengthwise of the platen as when military records are made which are much wider than the length of the usual carriage or platen, in which case the paper may be shifted along the platen to continue the writing or to write on two distinct parts of the paper.

A further object of the invention is to provide simple and efficient means whereby the platen may be properly line-spaced.

A still further object of the invention is to provide a platen carriage which may be readily made and assembled and which is effective in use.

With these and other objects in view, the invention will be hereinafter more particularly described with reference to the accompanying drawings, which form a part of this application, and will then be pointed out in the claims at the end of the description.

In the drawings, Figure 1 is a side elevation of one form of platen carriage embodying the invention.

Fig. 2 is a front elevation partly broken away.

Fig. 3 is a transverse section taken on the line III—III of Fig. 2; and

Fig. 4 is a plan view of one end of the platen carriage.

The carriage bed or support 10 may be of any suitable construction, and adapted to travel in any desired way along said bed or support is a carriage 11. This carriage has a base 12 and end sections or members 13. These end members 13 have upwardly extending curved and yielding arms 14 and 15, the latter being located in front of the platen 16 and the arms 14 at the rear thereof. These arms 14 and 15 act as springs and exert their force toward the center of the platen and form substantially a cradle for the platen. The platen 16 may be of the usual or of any preferred construction and has a rubber or other impact member 17 arranged around a form or cylindrical body 18 as usual. The platen is supported lengthwise thereof between rolls 19, 20, 21, and 22. These rolls 19 to 22 have their ends journaled in the carriage end member, the rolls 19 and 22 being journaled in the arms 15 and the rolls 20 and 21 being journaled in the arms 14 of the carriage. The platen is made substantially true throughout its entire length and the rolls 19 to 22 also run true in their bearings and are parallel to each other.

- 2
- and to the axis of the platen, and said rolls support the platen so that the latter maintains its alinement and rotates properly between said rolls.
- 5 The rolls 19 and 20 form a supporting bed for the platen and maintain their positions with respect to each other and to the carriage while the rolls 21 and 22 are adapted to move bodily toward or away from the 10 platen. The shaft of the roll 21 at the rear of the platen is movably held in adjustable bearings or in slots 23 in the upper ends of the arms 14, and said roll is forced radially inwardly by springs 24. The shaft of the roll 22 is similarly yielding and adjustably held in the upper ends of the arms 15, there being springs 25 located in slots in said arms for that purpose. The springs 24 and 15 20 permit manifolding by allowing the rolls 21 and 22 to move away from the periphery of the platen and such movement permits the platen for the same purpose to move away from the rolls 19 and 20. The springs as well as the yielding effect of the arms 14 25 and 15 maintain proper tension and frictional engagement between the rolls and the platen and said springs take care of any slight taper of the platen and insures it working in perfect alinement.
- 30 The paper 26 will extend between the platen and the rolls 21 and 20, and forward between the roll 19 and the platen, and upwardly between the roll 22 and the platen, as indicated in the broken lines, and takes 35 the usual course of a work sheet in the ordinary typewriter, and by reason of the tension of the springs 24 and 25 on the rolls 21 and 22, the work sheet will be held properly about the platen, and in such a way that the platen and all the rolls will rotate in unison. The paper is guided at the rear portion by a 40 paper apron 27 which is in the form of a curved metal plate. This paper apron is supported by projections 28 on the arms 14, and extends from the roll 19 to the roll 21 45 and even above said roll 21 if desired. At the front of the platen are arranged paper fingers 29 which are held to bosses or parts 30. The bosses or parts 30 are slidable along 50 a transversely extending graduated rod 31 and said fingers and the bosses are held in an adjusted position by means of thumb screws 32 or in any desired way. The fingers 28 and the paper apron 27 serve to guide 55 properly the work sheet about the platen. Above the platen and adapted to rest thereon is a guide plate 33 which assists in removing and directing the work sheet from the platen as indicated by the broken lines.
- 60 The plate 33 is supported between substantially T-shaped arms 34 which are loosely mounted upon the axis or shaft 35 of the platen at the ends thereof, and at one end of the arms 34 is a roll 36 which rests against 65 the feed roll 21 and serves to position the

arms 34 and the guide plate 33. The plate 33 rests by gravity on the surface of the platen and the roll 36 is simply to reduce friction and still position the arms 34 so that the paper may be fed to and about the 70 platen.

In case the work sheet is to be shifted lengthwise of the platen for the writing to be continued or the paper written on at different parts where sheets wider than the 75 carriage are used some means should be provided whereby the pressure on the platen may be released to permit adjustment of the paper. As one means, the arms 15 are adapted to be flexed to a certain extent, and 80 this flexing may be accomplished by means of an arm 37 the outer end of which has a finger or gripping part 38 by which said arms 15 and the roll 22 may be moved far enough to release the pressure on the platen 85 and permit the work sheet to be adjusted about the platen or lengthwise thereof as desired.

In the standard typewriter, the line-spacing means is axially arranged with respect 90 to the platen, but if the work sheet extends beyond the ends of the platen, the line-spacing means if thus arranged would be inaccessible even if it did not interfere with the work sheet itself. To avoid this, the 95 line-spacing means is mounted at the front of the platen. As shown, the roll 19 has a gear 39 on one end of its shaft, and this gear or pinion is in mesh with a larger gear 40. The gear 40 is rotatably held on a stud 41 100 mounted in a bracket 42 projecting outwardly and forwardly from the carriage. A ratchet wheel 43 is held to rotate with the gear 40, and adapted to engage the teeth of the ratchet wheel 43 is a pawl or dog 44. This pawl is held to an arm 45 the latter having a finger portion 46 to operate said arm. The arm is pivotally held at its inner end on the stud 41 and is provided with a projection, as 47, adapted to engage under a portion of the bracket 42 to position the arm substantially horizontally, but which permits upward movement of the arm. As the arm 46 is moved upwardly on its pivot the dog 44 will rotate the ratchet wheel 43, the 115 gear 40, and the pinion 39, and such rotary movement will impart a similar rotary movement to the feed roll 19, which, owing to its frictional engagement with the platen or the work sheet about the platen causes the 120 platen and work to move therewith a distance corresponding to the extent of movement of the arm 45. The arm 45 and pawl 44 may be arranged to give variable line-spacing as is provided in many kinds of 125 writing machines, though for ordinary purposes the construction shown may be employed to move the handle the distance of one, two or three or more teeth according to the distance the platen is to be moved for 130

the different lines of print. In addition to the line-spacing mechanism, the axis of the platen may be rotated independently of the line-spacing means by knobs 48 when the work sheet is of less length than the platen itself, it being understood that any suitable construction of line-spacing mechanism may be employed.

From the foregoing, it will be evident that a substantially floating platen is provided in which the usual end supports for the platen are dispensed with, and which is of such a construction that work sheets, large envelopes, etc., of different widths longer than the platen, may be suitably held about the platen to be written thereon; that the construction of the platen and carriage is such as to adapt the same for various kinds of writing machines; that simple and efficient means is provided for releasing the work sheet about the platen; that effective means is provided whereby the work sheet may be guided and held in proper position about the platen; and that simple means is provided whereby the work sheet may be properly line-spaced.

Having thus described my invention, I claim as new and desire to secure by Letters Patent:

30 1. In a typewriting machine, the combination of a carriage having end members provided with upwardly extending and curved arms forming a cradle, a platen, four radially spaced rolls mounted in said arms lengthwise of the platen and engaging the periphery of said platen to support the same frictionally and to adapt the platen to rotate with the rolls, said platen being free of any end support, and line-spacing means for rotating one of said rolls.

2. In a typewriting machine, the combination of a support, a carriage adapted to travel along said support and having end members provided with upwardly curved arms forming a cradle, a platen, rolls mounted in said arms lengthwise the platen at the upper and lower portions of said arms and engaging the periphery of said platen on opposite sides of the longitudinal axis to support the same, and line-spacing means for rotating one of said rolls.

3. In a typewriting machine, the combination of a support, a carriage adapted to travel along said support and having members provided with upwardly extending curved arms, a platen, two substantially T-shaped arms loosely mounted upon the axis of said platen at the ends thereof, a paper guide carried by said T-shaped arms, two spring pressed rolls mounted in the upper ends of said arms and extending lengthwise of the platen, one of said rolls forming a guide for the T-shaped arms, two rolls located under the platen on opposite sides of the longitudinal center thereof, a

paper apron carried by the first mentioned arms and extending lengthwise of the platen at the rear thereof, paper fingers adjustably mounted at the forward portion of the platen, and means for rotating one of the 70 rolls to rotate the platen and the work arranged about said platen.

4. In a typewriting machine, the combination of a support, a carriage adapted to travel along said support and having members provided with upwardly extending curved arms, a platen, a plurality of spring pressed rolls mounted in the upper portions of said arms and extending lengthwise of the platen, a plurality of rolls located under the 80 platen on opposite sides of the longitudinal center of said platen and forming a bed therefor, a paper apron extending lengthwise of the platen, and means for rotating one of the rolls to rotate the platen and the 85 work arranged about said platen.

5. In a typewriting machine, the combination of a support, a carriage adapted to travel along said support and having members provided with upwardly extending 90 curved arms, a platen, means for forcing one pair of arms away from the platen, two substantially T-shaped arms loosely mounted upon the axis of said platen at the ends thereof, two spring pressed rolls mounted in the curved arms and extending lengthwise of the platen, one of said rolls forming a guide for one end of the T-shaped arms the other ends of the arms carrying a paper guide, rolls located under the platen on opposite sides of the longitudinal center thereof, a paper apron carried by the curved arms and extending lengthwise of the platen at the rear thereof, paper fingers adjustably mounted at the forward portion of the 100 platen, and means for rotating one of the rolls to rotate the platen and the work arranged about said platen.

6. In a typewriting machine, the combination of a support, a carriage adapted to travel along said support and having members provided with upwardly extending and curved yielding arms, a platen, pressure rolls mounted in said arms, and means for forcing the arms on one side of the platen far enough 110 to release the pressure rolls to permit adjustment of the work about the platen.

7. In a typewriting machine, the combination of a support, a carriage adapted to travel along said support and provided with upwardly extending and curved yielding arms, a platen, rolls mounted in said arms to engage the work sheet on said platen, and a handle extending outwardly from one of the arms to spread said arms and release 115 the platen.

8. Work supporting and feeding mechanism for typewriting machines, comprising a carriage, two pairs of rollers extending longitudinally of the carriage at the front 120

and rear thereof adapted to frictionally engage the periphery of a cylindrical body at radially spaced points to center and revolvably hold the body, brackets held to each end of the carriage for supporting the rollers at their ends and formed with openings therein to adapt work of greater width than the carriage to be supported and fed by said rollers, a line space lever extending forwardly from said carriage and pivotally held at its rear end thereto, a ratchet wheel journaled on the carriage and located forwardly of said rollers, a pawl pivoted on the line space lever adapted to rotate the ratchet wheel, a gear wheel held to rotate with said ratchet wheel, and a gear held to rotate with one of the forward pair of rollers and meshing with said gear wheel.

9. In a typewriting machine, the combination of a support, a carriage adapted to travel along said support and having end members each of which is provided with a pair of upwardly extending resilient arms forming a cradle, a platen, rolls mounted in the upper and lower ends of each of said arms lengthwise of the platen and engaging the periphery of said platen to frictionally support the same and to adapt the platen to rotate with the rolls, said platen being free of any support except at its periphery, and line-spacing means located forward of the platen for rotating one of said rolls.

10. In a typewriting machine, the combination of a support, a carriage adapted to travel along said support and having end members provided with upwardly extending curved yieldable arms forming a cradle, a platen, rolls slidably and yieldably mounted in the upper ends of said arms lengthwise of the platen and frictionally engaging the periphery of the platen, rolls supported beneath the platen and frictionally engaging the platen lengthwise thereof, means for shifting one of said yieldable arms away from the platen, and line-spacing means located forward of the platen for rotating one of said rolls.

11. In a typewriting machine, the combination of a carriage, a platen, two rolls supported by the carriage and forming a bed for the platen, two yieldably held rolls supported by the carriage and exerting pressure radially of the platen at the front and rear thereof to hold the platen upon the bed rolls, and means for rotating one of the bed rolls to rotate the platen.

12. In a typewriting machine, the combination of a carriage, a platen, rolls forming a bed for the platen, rolls exerting a pressure radially of said platen at opposite sides thereof above the plane of the axis of the platen, means for rotating one of said bed

rolls to rotate the platen, and means for bodily shifting one of said pressure rolls out of contact with the platen.

13. In a typewriting machine, the combination of a carriage, a platen, rotary means mounted on the carriage and engaging the periphery of the platen below its axis to support and revolve the platen on the carriage, a roller engaging the periphery of the platen above the axis of the platen, means held to the carriage and extending upwardly therefrom at each end out of alinement with the ends of the platen for slidably and rotatably supporting the ends of said roller to adapt either or both ends of the roller to move away from the platen, yieldable means for normally pressing said roller against the platen, and means for actuating said rotary means to revolve the platen.

14. In a typewriting machine, the combination of a carriage, a platen, rolls supported on the carriage and forming a bed for the platen, rolls supported by the carriage and exerting pressure radially of said platen at opposite sides thereof above the plane of the axis of the platen, means for rotating the platen through the medium of one of said rolls, a paper apron between the rolls at the rear of the platen, a paper apron between the bed rolls, and paper fingers supported by the carriage between the rolls at the front of the platen.

15. In a typewriting machine, the combination of a carriage, a platen, rolls supported on the carriage, and forming a bed for the platen, rolls supported by the carriage and exerting pressure radially of said platen at opposite sides thereof above the plane of the axis of the platen, means for rotating the platen through the medium of one of said rolls, a paper apron between the rolls at the rear of the platen, a paper apron between the bed rolls, paper fingers supported by the carriage between the rolls at the front of the platen, and a paper guide supported between the upper rolls.

16. In a typewriting machine, the combination of a carriage, a platen, rolls forming a bed for the platen, rolls exerting a pressure radially of said platen at opposite sides thereof above the plane of the axis of the platen, means for rotating the platen through the medium of one of said rolls, means for guiding a work sheet about the platen, a work sheet deflector extending longitudinally of the platen between the upper rolls, and means held to the opposite ends of the platen for supporting said deflector.

This specification signed this 2nd day of March A. D. 1916.

PHILIPPE DE CLAMECY.
